(57) **CLAIM**

The ornamental design for a mobile phone case with integral virtual reality 3D viewer, as shown and described.

DESCRIPTION

FIG. 1 is a front elevational view of a mobile phone case with integral virtual reality 3D viewer showing my new design, wherein the virtual reality glasses are in a stowed condition within the mobile phone case;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof;

FIG. 9 is a second front elevational view of the mobile phone case with integral virtual reality 3D viewer of FIG. 1, wherein the virtual reality glasses are shown in an unfolded condition;

FIG. 10 is a rear elevational view thereof;

FIG. 11 is a left side view thereof;

FIG. 12 is a right side view thereof;

FIG. 13 is a top plan view thereof;

FIG. 14 is a bottom plan view thereof;

FIG. 15 is a perspective view thereof; and,

FIG. 16 is another perspective view thereof.

The broken lines shown form no part of the claimed design.
